TRAILER-TRUCK LIGHT CONNECTION

Hugh D. Kissick, Belle Fourche, S. Dak.

Application October 2, 1950, Serial No. 187,935

1 Claim. (Cl. 339—49)

1

This invention comprises novel and useful improvements in electric cable couplings, and more particularly pertains to electric cable couplings for trucks.

An important object of this invention is to provide an electric cable coupling which may be readily coupled and uncoupled, and which coupling will not become disconnected under normal conditions of use, and which coupling may nevertheless be disconnected in response to a tension on one of the coupling members which will rotate the members relative to each other.

Another important object of this invention is to provide an electric cable coupling, in which the contact terminals of the coupling are effectively sealed against the admission of moisture or other foreign matter, when the coupling is connected.

Yet another object of this invention is to provide a cable coupling, in accordance with the foregoing objects, in which the contact terminals of the coupling are yieldingly biased into engagement with each other, and in which the electrical conductors are connected to the contact terminals in an improved manner.

An important feature in this invention resides in the provision of a pair of identical body members adapted to be disposed in pivotal overlapping engagement, each of the members having an arcuate flange on one end, and an arcuate channel adjacent the other end thereof for receiving the flange, and a plurality of electrical contact terminals disposed on the registering faces of the body members, which terminals are in registry with each other when the body members are disposed in a predetermined angular position relative to each other.

Another important feature of this invention resides in the provision of a cable coupling, in accordance with the foregoing feature, in which each of the body members has an annular sealing ring carried by the registering faces thereof, which sealing rings and both of the members are adapted to abut each other to prevent the admission of moisture and other foreign matter disposed within the channel defined by the annular sealing ring.

Still another feature of this invention resides in the provision of an electrical cable coupling, in accordance with the foregoing feature, together with an insulator block disposed within a transverse bore in each of the members, with a bore in each of the insulator blocks having a contact terminal reciprocably disposed therein, and yieldingly biased into engagement with the registering contact terminal carried by the other of said blocks.

Yet another feature of this invention resides in the provision of a coupling having insulator blocks therein, in accordance with the foregoing feature, in which the guide rod is carried by

2

each of the contact terminals, with a cap member carried by each of the guide rods to limit reciprocation of the terminal within the bores in the insulator block, which caps are threadedly received on the guide rods, and which are provided with a transverse bore for receiving an electrical conductor, the guide rod being adapted to engage the conductor to lock the conductor to the cap.

These, together with various ancillary objects and features, are attained by this device, a preferred embodiment of which has been illustrated by way of example only in the accompanying drawings wherein:

10 Figure 1 is a side elevational view of the electrical cable coupling, with the body members thereof shown coupled together;

15 Figure 2 is a top plan view of the electrical cable coupling;

20 Figure 3 is a longitudinal sectional view of the cable coupling, taken substantially on the plane 3—3 of Figure 2;

25 Figure 4 is a plan view of one of the body members, showing the contact terminals arrangement;

Figure 5 is a fragmentary plan view of the other of the body members, also showing the contact terminal arrangement;

30 Figure 6 is a plan view of one of the body members with the cover thereof removed to show the manner in which the conductors are connected to the contact terminal; and,

35 Figure 7 is a fragmentary sectional view of one of the contact terminals.

Reference is now made more specifically to the accompanying drawings wherein like numerals designate similar parts throughout the various views, and in which the electrical cable coupling, indicated generally by the numeral 10, includes first and second body members 12 and 14, respectively.

40 Each of the body members 12 and 14 are formed identical to each other, and accordingly a discussion of one of the body members is thought sufficient, it being understood that the same or a similar construction should be utilized in the other of the body members.

45 The member 12 includes a substantially cylindrical sleeve portion 16 having an arcuate flange 18 on one end thereof, and an elongated portion 20 on the portion thereof diametrically opposed to the flange 18. A lug 22 having an arcuate inner face 24, disposed concentric with the cylindrical sleeve 16, is formed integrally with the elongated portion 20, and has an arcuate channel 26 formed therein, which channel is adapted to receive a flange 18 of the body member 14, the flange 18 of the body member 12 being adapted to be received in a similar channel 26 formed in the body member 14. As will be appreciated, the flange 18 is provided with an

arcuate rib 28, the channel 26 having a correspondingly formed arcuate recess 30, for the reception of the corresponding rib carried by the flange of the other body member 14.

The elongated portion 20 is preferably provided with an internal passageway 32, which passageway communicates with the interior of the sleeve 16, whereby conductors such as 34 may be disposed in the passageway. In order to limit relative pivotal movement of the body members 12 and 14, there may be provided locking pins 34 which are adapted to engage the flanges 18, each of which pins is secured to the lug 22 and the elongated portion 20, transversely of the channel 26, as is clearly apparent from a consideration of Figure 1.

The sleeve 16 is provided with an annular groove 36, adjacent the base 38 of the body member 12 which is adapted to register with a corresponding base of the body member 14, the groove 36 receiving the rib 40 which is carried by an annular resilient ring 42. The ring 42 has a face 44 which is adapted to abut the corresponding face of an annular ring carried by the other body member 14, to provide an effective moisture seal between the two body members, when the latter are connected together. An electrical insulator block 46 is disposed within the sleeve 16, and non-rotatably connected thereto by means of the set screw 48, the block having a portion thereof extending into the resilient ring 42, to retain the latter in position in the sleeve 16. The insulator block 46 is provided with a plurality of bores 50 therein which extend parallel to the axis of the block, each of which bores has an internal annular flange 52 intermediate the ends thereof to guidingly receive a shaft 54. Although seven of such bores are shown, it is to be understood that any number of the same may be utilized without departing from the spirit of the invention, and that the bores need not be disposed in the concentric arrangement shown best in Figures 4, 5 and 6, but may take any suitable pattern which is deemed desirable for the particular coupling. The contact terminal 56 is carried by one of the shaft 54, and a spring 58 is interposed between the terminal 56 and the annular flange 52, to yieldingly bias the terminal 56 in a direction to engage the corresponding terminal carried by the other body member 14. A cap member 60 has an internally threaded bore 62 therein, which bore receives the correspondingly threaded end portion 64 of the shaft 54, the cap member 60 also having a transversely extending conductor-receiving bore 66 which communicates with the bore 62, whereby the shaft 54 may be urged into engagement with the end of the conductor 34 which is inserted in the bore 66. As will be appreciated, the cap member 60 is reciprocably disposed within the bore 50, the lower portion of the cap member engaging the annular flange 52, to limit reciprocation of the terminal 56 within the bore 50.

The resilient pad 68, of electrically insulating material, overlies the upper portion of the insulator block 46, and the cap member 60, to electrically insulate the cap member 60 from the body members 12 and 14, and a cover plate 70 having a peripheral flange 72 is seated in a corresponding recess 74 in the outer face of the body members 12 and 14, the cover member being secured in position by means of suitable fasteners 76, whereby the cover member will retain the pad 68 and the insulator block 46 in position within the sleeve 16.

In operation, it will be appreciated that the body members 12 and 14 may be selectively coupled and uncoupled from each other by merely rotating the body members 12 and 14 relative to each other. It is also thought apparent that the coupling 10 may be so disposed on the truck that the conduits (not shown) which holds the conductors 34 is normally aligned with the body members 12 and 14 in a direction longitudinally of the coupling, whereby disconnection of the coupling will be prevented.

It is also thought apparent that when the body members 12 and 14 are coupled to each other, that the contact terminal 56 will be yieldingly biased into engagement with the corresponding contact terminal carried by the other body member, and that the annular resilient ring 42 will have the face 44 thereof in abutting engagement to prevent the admission of moisture or other foreign matter to the contact terminal 56.

From the foregoing, it is thought that the operation and construction of the device will be readily understood, and further discussion therefore is believed to be unnecessary. However, numerous modifications will readily occur to those skilled in the art after a consideration of the foregoing specification and accompanying drawings, it is not intended to limit the invention to that shown and described, but all suitable modifications may be resorted to falling within the scope of the appended claim.

Having described the invention, what is claimed as new is:

A cable connector comprising a pair of substantially elongated body members adapted to have portions thereof disposed in pivoted overlapping engagement, means for positioning said body members in a predetermined angularly adjusted position with respect to each other, each of said members having a transverse bore therein, an insulator block in each of said bores, said insulator blocks providing opposed registering faces when said body members are engaged, each of said insulator blocks having a plurality of bores parallel to the axis of the transverse bores in said body members, a counterbore at each end of said bores, contact rods slidably mounted in said bores, contact heads on said rods, resilient members in the counterbores under said contact heads, cap members threadedly connected to the other end of said contact rods, each of said caps having a transverse conductor receiving opening therein intersecting the threaded connection, said contact heads registering with each other when said body members are disposed in said predetermined angularly adjusted position, a cover plate attached to the external face of each of said body members, and a resilient insulating pad interposed between said cover and said insulator block.
